SCALPEL

Sol Rothschild, Brooklyn, N. Y.

Application February 11, 1936, Serial No. 63,362

21 Claims. (Cl. 30—125)

This invention relates to improvements in surgeons' scalpels and scalpel blades and has for its main object to provide an improved scalpel with a magazine connected thereto for holding separate blades of the type employed in surgical operations.

A further object is to provide a simple, efficient and positive means for feeding such surgeons' blades from the magazine to the holding means connected with the scalpel handle and secure same in such proper position without endangering the cutting edge thereof while being fed and means for ejecting the used blade therefrom all by the mere manipulation of a single control member.

A further object of this invention is to provide such a scalpel of the magazine type with means for interchanging a surgeon's blade in the holding means without feeding a blade from the magazine.

A further object of the invention is to adapt the magazine of such a scalpel knife or the like, with means for holding and feeding such surgeons' blades having various shaped cutting edges so that the cutting edges will not be destroyed, distorted or dulled while being so held or fed.

A further object of the invention is to provide such a scalpel with a feeding and holding device which will hold such surgeons' blades firmly, securely and accurately while being fed to and after received in said holding means and said device also cooperating to release said blades therefrom when desired.

These together with other objects will now be more particularly described by referring to the enlarged scale drawing, wherein:

Figure 1 is a half top elevational view and a half top sectional view taken on the line 2—2 of Figure 2 and having added thereto in section a sliding member of the handle.

Figure 2 is a side view of the magazine scalpel taken along the line 1—1 of Figure 1 with the sliding member of the handle omitted.

Figure 3 is a complete top elevational view.

Figure 4 is a section taken along the line 3—3 of Figure 1.

Figure 5 is a perspective of the blade clip.

Figure 6 is a perspective of the blade clip cover.

Figure 7 is an inside view of the blade receiving jaw and that part of the holding means on the sliding member of the handle.

Figure 8 is an end view of that which is shown in Figure 2.

Figure 9 is an end view of that which is shown in Figure 3.

The magazine scalpel, itself, is designed to be compact so as not to be cumbersome and also maintain to a high degree lightness which is the surgeon's preference in an operating knife. It is so constructed that the feeding of blades from the magazine to the positive and accurate holding means and the ejection of the used blade from the holding means are both accomplished by the mere manipulation of a single member.

The holder, itself, may be said to include a handle 10 having a sliding member 11 connected therewith. At one end of the handle 10 and at the corresponding end of the sliding member 11 are provided blade holding jaws 12 and 13 respectively. The jaw 12 is recessed the thickness of a blade at 14 so as to accommodate the seating of a surgeon's blade 15 on a portion of its unsharpened top, its unsharpened bottom part and rear end. This jaw also has recesses 16 corresponding in shape and relative position to the apertures 17 in the blade 15 when said blade is so seated in the recess 14 as shown in the drawing. When the jaw 13 is brought adjacent jaw 12, with a blade thereon, the blade 15 is urged into the recess 14 by the tie bar 18 actuated by springs 19 and said bar having connected on either end positioning studs 20, preferably square, which engage in the blade apertures 17. As the bar 18 is actuated and the blade 15 seated in the recess 14 the positioning studs 20 engage in the recesses 16 in the jaw 12 and together with the recess 14, the bar 18 and jaws 12 and 13 hold the blade firmly, securely and accurately in place. The bar 18 with its studs 20 thereon and springs 19 being the movable members of the jaw 13, are held in place by shouldered pins 21 which are fixed to the bar and made to pass thru the case of the housing 22, formed on the jaw 13 and provided to accommodate the immediately described mechanism in the jaw 13. It is obvious the jaw 13 as a whole could be made movable, if desired, instead of its members described above.

Though the studs 20 are preferably made square shaped they have their rear ends, however, rounded off as shown at 23 so that when it is desired to eject the blade 15 from its holder it is merely necessary to draw the sliding member 11 back and the positioning studs 20 ride out of engagement from the recesses 16 and blade apertures 17 as the rear part of the recess 14 pushes the blade forward and out of the holder. It should be observed that during this

operation as the studs 20 ride out of engagement with the recesses 16 and apertures 17 they bear against the blade and act to keep it in the recess 14 in the jaw 12, and out of alignment with the jaw 13 until the jaws have completely cleared each other, thus preventing the possibility of jamming the instrument as the slide 11 is drawn back.

The jaw 13 and sliding member 11 are made slidably movable with respect to the jaw 12 and handle 10 and are held to each other by interlocking one into the other as, for instance, shown at 24, Figure 9. The jaws 12 and 13 are shaped so as to allow plenty of clearance to the cutting edges of the various odd shaped types of surgeons' blades and yet give ample support thereto as clearly indicated at 25, Figures 2 and 7.

At some convenient place on the handle 10, preferably the end opposite the holding jaws, is connected a watertight magazine made so as to afford protection to a plurality of sterilized surgeons' blades held therein. Because surgeons' blades come in various sizes and many different shaped cutting edges to suit the individual needs as well as the particular preferences of different surgeons, I prefer to provide a blade clip as shown in Figure 5 to hold the blades instead of inserting these blades separately into the magazine, for, it is necessary with blades of this character to hold them in a particular fashion in order to afford proper protection to their cutting edges and also to have other means on said clip to insure cutting edge protection. I have found the particular type of clip best adapted for this purpose has a side wall 26 with a front end wall 27 and a rear end wall 28 and a top wall 29. Fixed on the inside of the side wall 26 are positioning studs 20' extending in height so as to be on a perfect line with the outermost surface of the topmost blade in the clip. These studs position said surgeons' blades, which have odd shaped cutting edges, in such a predetermined position so as to afford perfect protection to their cutting edges. It might be well to note that the preferred position of said studs is such as to hold the rear unsharpened portion and part of the top unsharpened portion of the blade against the rear end wall and top wall of the clip respectively. With such an arrangement it is evident a surgeon will not be limited to loading the magazine with any one type of blade but may include various shapes in one loading, if desired, and thus obtain quick changes of more beneficial types of cutting edges for particular stages of the operation. Extending on the outside of the front end wall 27 are flanges 30 and 31 and on the outside of the rear end wall 28 are flanges 30' and 31'. The flanges 30 and 30' are bent back and then out forming the angle of a square over which is snugly slidable and interlocking therewith a blade clip cover, Figure 6, which retains the blades in said clip when not in use.

The magazine is formed by the top wall 32, bottom wall 33, front wall 34 and rear wall 35 with the left side closed by the sliding member 11 and the right side having a door 36 hinged at 37. When the door is opened as shown by dotted lines the clip full of blades is inserted in the magazine after the clip cover has been removed. The front end and rear end wall flanges 30 and 31, and 30' and 31' respectively have grooves 38 and 39 to engage projections 40 and 41 on walls 34 and 35 to properly align the clip as it is inserted in the magazine with the side wall 26 towards the door opening. The clip is slid all the

way into the magazine until the square angle part of the flanges 30 and 30' are pushed flush against the projections 42 and 43 on the walls 34 and 35 respectively to properly align the clip longitudinally. When the door of the magazine is closed the clip is held in this position by projections 44 and 45 on the inside of the door 36 which bear against the side wall 26 of the clip. The side wall 26 has apertures 46 therein to permit the free passage of plates 47. These plates 10 thus engage the face of the nearest blade and under the action of the compression coil springs 48, fixed thereto and to the cover, forces the blades to the left.

When it is desired to feed a fresh blade from the magazine to the holding means, between jaws 12 and 13, the sliding member 11 is drawn back until it is stopped by the projection 49 connected on its upper right side by a similar projection 50 on the outer top wall 32 of the magazine. In this position the jaw 13 is in receiving position and in alignment with the blades in the magazine and the topmost blade is free to be ejected therefrom. The jaw 13 like the jaw 12 has a similar recessed portion 14' which receives the blade as it is ejected. Now it will be observed that when the jaw 13 is in this receiving position the spring urged positioning studs 20 in the jaw are in perfect line with and resting against the positioning studs 20' in the clip, thus a surgeon's blade with any odd shaped cutting edge may be fed from the magazine onto such positioning studs and into such a receiving jaw 13 without moving out of alignment in any direction. This is most important in the feeding of surgeon's blades as their edges must never be endangered. The sliding member 11 is then pushed forward with the blade held in the recess 14' and on the positioning studs 20 and against the inside wall of the handle 10 wherein the studs 20 engage in the groove 51. When the jaw 13 is brought opposite the jaw 12 the blade is positioned as before described. In order to prevent running past the point of proper positioning a projection 52 on the sliding member 11 is provided to bear against the projection 50 on the top outside wall of the magazine thereby stopping it in accurate positioning alignment. It should be noted that projection 52 or 50 may be hinged if desired so that when in position they would act as stops and when swung out of position would permit the sliding apart of the instrument for thorough cleaning.

In order to insure the positioning studs 20 in the jaw 13 to ride freely over the pack of blades at the pointed part of the cutting edges or wherever else necessary a flange 53 is provided on the clip extending from the front wall 27 inwardly towards the blade, cut to the shape of the blade or any other suitable shape and so disposed that the spring urged studs 20 will glide freely over the pack.

As a further means to make this scalpel fool-proof I provide spring urged bearings 54 which are fixed to the sliding member 11 so that as same is slid from one position to another the bearings depress the blades in the pack and together with the positioning studs in said clip prevent the topmost blade from moving or sliding out of the clip, before the proper time, thereby preventing jamming of the instrument.

It should be observed that a blade in the holding means, between the jaws 12 and 13, may be ejected therefrom and any other shaped surgeon's blade inserted therebetween and locked into po

sition without disturbing the blades in the magazine if so desired. This may be accomplished by merely sliding the jaws opposite from each other the limited distance necessary to take the old 5 blade out and insert a new blade therein. In a like manner a blade may be used and after use removed from its holder for cleaning and resterilizing, without disturbing the blades in the magazine, and then replaced.

10 Although there are many ways to pack such surgeons' blades for delivery to the consumer, because it is necessary to deliver them sterilized and ready for use I propose to insert the entire clip of blades, after being sterilized, into a sterilized bottle and seal same with a sterilized stopper.

Now as to surgeons' blades it should be definitely understood that they come in many odd and irregularly shaped cutting edges which, by now, have become somewhat standardized and 20 their uses have become quite well established. These cutting edges come hooked shaped, diagonal shaped, rounded, pointed, blunted and others which I do not mention to avoid unnecessary prolixity but, all of which my instrument 25 will accommodate and feed from the magazine to the holding means without destroying, distorting or dulling said cutting edges. I do not propose to make any suggestions or changes with regard to the shapes of said cutting edges 30 but so little attention has been given the rear unsharpened portion of surgeons' blades, which I have found to be of just as great importance as the cutting edge itself, I feel the importance of bringing forth the following feature of my 35 blades. In known blades of the surgeon's type the rear unsharpened portion thereof has been manufactured with most of its edges curved and I have found that curved surfaces always allow a certain amount of play even when employed 40 in such a type of handle provided with recesses to fit such rear unsharpened portion when held in the holding means, therefore I prefer to make the rear portion of my blade square as clearly shown in the drawing. Such a shape, I have 45 found, provides the best method of holding such surgeons' blades firmly, securely and accurately in position, when seated in a recess of corresponding shape such as I employ. In any event, however, the top and bottom edge of said unsharpened 50 portion which engages in such a recess should be parallel to each other. Though I recommend this particular type of blade as best, it should be clearly understood that my instrument 55 will accommodate blades with any shape backs.

The instrument is illustrated with half of its handle sliding with relation to the other half but I do not wish to be confined to this arrangement nor the arrangement of its other parts as 60 it is evident other arrangements of parts can be devised to obtain all of the results set forth, my invention residing in a scalpel that will successively and successfully feed surgeons' blades from a stack to the holding means so that their cutting edges will not be destroyed, distorted or dulled while being so fed and the invention is 65 designed to include such equivalent motions and mechanisms as will bring about such a result.

70 While I describe my invention as particularly applied to surgeons' scalpels, it is to be understood that the invention may be employed in other blade delivery devices without departing from the spirit or terms of the invention as set forth.

75 Having thus described my invention what I

claim as a new and useful article of manufacture is:

1. A scalpel comprising a handle with a blade holding means connected thereto for holding a surgeon's blade so that it will project beyond the front end of the holding means, a surgeon's blade substantially as set forth, means in said holding means for fixing said blade firmly and securely in accurate position therein, a magazine for separate surgeons' blades connected to said handle, means in said magazine for holding a stack of said surgeons' blades in predetermined orderly relationship so that the cutting edges of said surgeons' blades will be fully protected, means in said magazine for ejecting a blade therefrom, means connected with said handle for receiving said blade as it is ejected from said magazine and for holding same firmly, securely and accurately in a predetermined fixed position so as to protect the cutting edge of said surgeon's blade, and said last named means feeding said blade from said last position endwise to the holding means position and there cooperating to fix said blade firmly, securely and accurately in the holding means. 25

2. A scalpel comprising a handle with a blade holding means connected thereto, a surgeon's blade substantially as set forth, means in said holding means for fixing said blade firmly and securely in accurate position therein, a magazine for separate surgeons' blades connected to said handle, means in said magazine for holding a stack of surgeons' blades in predetermined orderly relationship so that the cutting edges of said surgeons' blades will be fully protected, 30 means in said magazine for ejecting a blade therefrom, means in said handle for receiving said blade as it is ejected from said magazine and for holding same by a part of its unsharpened portion with the cutting edge extending 35 therefrom and so held firmly, securely and accurately in said position so as to protect the cutting edge of said surgeon's blade, said last named means feeding said blade from said last 40 position to the holding means position, and said last means comprising a movable member for 45 cooperating to fix said blade firmly, securely and accurately in the holding means when it is in holding means position, and means on said feeding means for keeping the topmost blade 50 on said stack from being ejected from said magazine until said receiving means is again brought into alignment with the blades in said magazine.

3. A scalpel comprising a handle with a blade holding means connected thereto for holding a surgeon's blade so that it will project beyond the front end of the holding means, a surgeon's blade substantially as set forth, means in said holding means for fixing said blade firmly and securely in accurate position therein, a magazine for separate blades connected to said handle, means in said magazine for holding a stack of surgeons' blades in predetermined orderly relationship so that the various shaped cutting edges of said surgeons' blades will be fully protected, 65 means in said magazine for ejecting a blade therefrom, means connected with said handle for receiving said blade as it is ejected from said magazine and for holding same firmly, securely and accurately in predetermined fixed position so as to protect the cutting edge of said surgeon's blade, said last named means feeding said blade from said last position endwise to the holding means position and there 70

75

cooperating to fix said blade firmly, securely and accurately in the holding means, and means on said feeding means for keeping the topmost blade on said stack from being ejected from 5 said magazine until said receiving means is again brought into alignment with the blades in said magazine, and the used blade adapted to be released from said holding means as said feeding and receiving means is drawn away from the 10 holding means position.

4. A scalpel comprising a handle with a blade holding means connected thereto for holding a surgeon's blade so that it will project beyond the front end of the holding means, a surgeon's 15 blade substantially as set forth, means in said holding means for fixing said blade firmly and securely in accurate position therein, a magazine for separate surgeons' blades connected to said handle, means in said magazine for holding 20 a plurality of surgeons' blades in predetermined orderly relationship so that the various shaped cutting edges of said surgeons' blades will be fully protected, means in said magazine for ejecting a blade therefrom, means connected 25 with said handle for receiving said blade as it is ejected from said magazine and for holding same firmly, securely and accurately in predetermined fixed position so as to protect the cutting edge of said surgeon's blade, said last 30 named means feeding said blade from said last position endwise to the holding means position and there cooperating to fix said blade firmly, securely and accurately in the holding means, said blade adapted to be released from said 35 holding means as said feeding and receiving means is drawn away from the holding means position, and means on said feeding and receiving means for releasing the topmost blade in said magazine and permitting it to be ejected 40 therefrom when said feeding and receiving means is moved into alignment with the blades in said magazine.

5. A scalpel comprising a handle with a blade holding means connected thereto, a surgeon's 45 blade substantially as set forth, means in said holding means for fixing said blade firmly and securely in accurate position therein, a magazine for separate surgeons' blades connected to said handle, means in said magazine for holding a 50 stack of separate surgeons' blades in predetermined orderly relationship so that the various shaped cutting edges of said surgeons' blades will be fully protected, means in said magazine for ejecting a blade therefrom, means connected with 55 said handle for receiving said blade as it is ejected from said magazine and for holding same firmly, securely and accurately in predetermined fixed position so as to protect the cutting edge of said surgeon's blade, said last named means 60 feeding said blade from said last position endwise to the holding means position and there cooperating to fix said blade firmly, securely and accurately in the holding means, said blade adapted to be released from said holding means 65 as said feeding and receiving means is drawn away from the holding means position, and means on said feeding and receiving means for releasing the topmost blade in said magazine and permitting it to be ejected therefrom when 70 said feeding and receiving means is moved into alignment therewith, and cooperating means on said handle for preventing said feeding and receiving means from being moved out of alignment with the blades in said magazine when 75 moved to receive a blade therefrom and out of

proper holding position when feeding a blade thereto.

6. A scalpel comprising a handle with a surgeon's blade holding means connected therewith, positive positioning means in said holding means 5 for holding said blade immovably, a magazine for separate surgeons' blades, and positive means for successively feeding such types of blades from the magazine endwise to the positioning means in the holding means, and said feeding means 10 being adapted to release said blade from the positive holding means as it is moved out of said holding means position.

7. A scalpel comprising a multiple part handle with a blade holding means connected therewith, 15 said blade holding means comprising a male and female member for engaging in male and female relationship with each other, a magazine of blades connected to one of said handle members, and positive means for successively feeding blades 20 from the magazine into the holding means and in engagement between said male and female members, said female member being restricted to receive said male member in complementary relationship therein to predetermine the position 25 thereof.

8. A scalpel comprising a handle with a magazine for holding a stack of surgeons' blades connected in a substantially longitudinally parallel relationship therewith, a blade holding means 30 firmly fixed in a substantially longitudinally parallel relationship to said handle, means in said magazine for ejecting a surgeon's blade therefrom, and a slide movable on the handle and having means thereon for receiving and holding 35 said ejected surgeon's blade in a firm predetermined position so as to protect its cutting edge and for moving said blade in said position to the holding means.

9. A scalpel comprising a handle with a blade 40 holding means connected therewith, said blade holding means comprising a pair of jaws for holding a blade therebetween and said jaws having blade holding and positioning means therein, said jaws being movable both towards and away from 45 each other whereby the holding means therein is moved in relation thereto, a magazine for separate surgeons' blades, and positive means for successively feeding said surgeons' blades from the magazine to the operating position in the holding means.

10. A scalpel comprising a handle with a blade holding means connected therewith for holding a surgeon's blade so that a portion of said blade will extend outside of said holding means, said 55 blade holding means comprising a pair of jaws having blade holding and positioning means therein for retaining the blade firmly and securely in the holding means, said jaws being movable both towards and away from each other, 60 a magazine for separate surgeons' blades, positive means for successively feeding said surgeons' blades from the magazine and endwise into the positioning means and into the holding means, and means actuated by the movement of said 65 jaws in opposite relation to each other for releasing said surgeon's blade so that it will fall from the holding means.

11. A scalpel comprising a surgeon's blade holding device, a handle, a blade magazine connected 70 thereto, a blade clip having a recess therein for holding a plurality of surgeons' blades insertable and removable in said magazine, said blades having apertures therein, said blade clip having positioning studs therein for engaging the apertures 75

- in said blades for aligning same in said clip and for holding same in alignment and guiding same when being fed therefrom, means in said magazine for aligning said blade clip therein, means 5 for ejecting a blade at a time from said magazine, and guide means for receiving said blade in said aligned position and firmly holding same in said position and for advancing said blade in said position towards said blade holding device.
- 10 12. A scalpel comprising a surgeon's blade holding device, a handle, a blade magazine connected thereto, a blade clip having a recess therein for holding a plurality of surgeon's blades insertable and removable in said magazine, said blades having 15 apertures therein, said clip having means therein for engaging the apertures in said blades for aligning same in said clip so as to fully protect their cutting edges and acting as alignment guides when said blades are fed therefrom, 20 means for advancing a surgeon's blade from said clip into the holding means, said holding means comprising means therein for engaging the apertures in said blades and means for disengaging said blade engaging means whereby the blades 25 will drop from the holding device.
13. A knife comprising a handle with a blade holding device, a magazine of blades, a slide movable longitudinally on the handle for directly and positively feeding a blade at a time from the 30 magazine beyond the front end of the holding device, said slide including cooperating means to fix said blade firmly and securely in the holding device in said last position, and said slide adapted to release said blade from said holding device as 35 it is moved out of holding means position.
14. A knife comprising, a multiple part handle, a multiple part blade holding means connected with said handle in substantially longitudinally parallel relationship thereto and said holding 40 means having a blade engaging member therein for holding a blade firmly and securely in projected position from the front end of the holding means, a magazine with a plurality of blades therein, means for feeding said blades one at a time from the magazine endwise into the holding 45 means in engagement with said blade engaging member, and said holding means parts being movable toward and away from each other to open and close the holding means actuated by 50 relative movement of the handle members so that the blade may be removed therefrom and a new blade inserted therein without feeding a blade from the magazine.
15. In a blade delivery device, a handle, a magazine of blades connected therewith, and a blade 55 holding means into which the blades are fed one at a time, and a means for ejecting a blade at a time from the magazine, a slide having a means therein for receiving said blade as it is ejected from the magazine and holding a blade firmly and securely in a predetermined fixed position and said slide feeding said blade in said position into the holding means.
16. In a magazine knife having a blade holding 60 means thereon and a magazine for holding a plurality of blades and means for ejecting blades therefrom, a blade feeding means adapted to receive and engage a blade at a time as it is ejected from said magazine and hold same firmly
- and securely, in combination with a blade having means therein for interlocking with said feeding and engaging means, said feeding and engaging means retaining its engagement with said blade after said blade is fed into the blade holding means cooperating to position and hold said blade therein, and means for causing the separation of said blade and said engaging means when the latter is moved out of holding means position. 5
17. A knife comprising, a substantially longitudinally extending handle with a blade holding means for holding a blade projected beyond the front end thereof in a substantially longitudinally parallel relationship to the longitudinal plane of 15 said handle, a magazine of blades, means for directly and positively feeding a blade at a time from the magazine into the holding means beyond the front end thereof, and means in the holding means for firmly locking said blade therein in 20 said last projected position.
18. A knife comprising, a substantially longitudinally extending handle with a blade holding device for holding a blade projected beyond the front end thereof in a substantially longitudinally parallel relationship to the longitudinal plane of 25 said handle, a magazine of blades, means for feeding a blade at a time from the magazine into the holding means beyond the front end thereof, and means in the holding means for positively holding said blade in said last projected 30 position in a substantially longitudinally parallel relationship to the longitudinal plane of said handle, and means for releasing said blade from said holding device. 35
19. A knife comprising a magazine of blades, a blade holding means having a movable blade engaging member therein for locking a blade firmly in the holding means, means for feeding a blade at a time from the magazine into the holding means in engagement with said blade engaging member, and means for releasing said blade from said engaging member and the holding means whereby it is pushed out of the holding means. 40
20. A knife comprising, a substantially longitudinally extending handle, a magazine in said handle, a blade holding means forming part of the longitudinally extending handle and having means therein for positively holding a blade firmly and securely projected from the front end thereof in substantially longitudinally parallel relationship to the longitudinal plane of the handle, and means for successively feeding blades 45 from the magazine into the holding means. 50
21. A knife comprising, a substantially longitudinally extending handle with a blade holding device for holding a blade projected beyond the front end thereof in a substantially longitudinally parallel relationship to the longitudinal plane of the handle to allow free cutting therewith the entire width of the blade, means for positively holding said blade in said projected position, a magazine with a plurality of blades, and a means for feeding said blades in succession from the magazine into said free cutting 60 position in the holding device. 65

SOL ROTHSCHILD.
